(57) **CLAIM**

The ornamental design for a bracket for pedestal fan with display for fan control, as shown and described.

DESCRIPTION

FIG. 1 is a perspective view of the bracket with display for fan control showing our new design;

FIG. 2 is a front elevational view thereof;

FIG. 3 is rear elevational view thereof;

FIG. 4 is a top plan view thereof;

FIG. 5 is a left side elevational view thereof; and,

FIG. 6 is a right side elevational view thereof.

The indicia shown in FIGS. 1–6 does not form part of the claimed design.
